DEVICE FOR LOCKING PLATENS OF
TYPEWRITERS

Jules Paul Camzi, Geneva, Switzerland

Application December 6, 1943, Serial No. 513,104
In Switzerland March 15, 1943

7 Claims. (Cl. 197—141)

This invention relates to accessories for typewriters in the form of regulating devices for the platen roller feed whereby rotation of the platen and feed of the paper can be arrested at any predetermined line of writing and the operator can ascertain at a glance the number of lines written on a sheet and the number of lines remaining.

The primary object of the invention is to provide a simple and reliable device of this kind.

The device according to the invention comprises an internally toothed crown coaxial with the platen roller and having a series of notches around its periphery, a pinion in constant engagement with the teeth of said crown, said pinion being rotatable by said platen roller to turn said crown at slow speed relatively to said roller, a stop member rotating with said crown, said stop member being settable coaxially with said crown to engage any of the notches therein, and a fixed stop in the path of said rotating stop member and arranged to block further movement thereof and of the platen roller when said platen roller has turned through a predetermined angle of paper feed.

The accompanying drawing, which is given solely as an example, shows several embodiments of said invention. In the drawing:

Fig. 1 is a front view of a first embodiment, whereas Fig. 2 shows a side view in partial section, and Figs. 3 and 4 show details.

Fig. 5 is a side view of a second embodiment, Fig. 6 is a longitudinal sectional view, Figs. 7 to 11 illustrate details, and Figs. 12 to 14 show, on a larger scale, further details of the device.

Figs. 16 and 17 show a third embodiment.

In the modification shown in Figs. 1 to 4, the shaft 1 of the usual platen roller 2, the rotation of which feeds the paper sheet, not shown, extends through three discs 3, 4 and 5, and can turn relatively thereto, whereas a pinion 6 is fixed to this shaft 1 and is constantly in mesh with a pinion 7 which can rotate about a shaft 8 fixed to the disc 3, which latter is itself fixed to the usual carriage 9 whereby said disc 3 is unable to revolve. The pinion 7 is in mesh with an internal toothed crown 10 on the disc 4. Said disc has external slots 11 into each of which can penetrate a part 12 of a stop 13 fast on the disc 5 which latter is pushed by a spring 14 located between this disc and the usual roller turning knurled knob 16. The stop 13 is adapted to thrust against another stop 15 fixed on the disc 3.

The pinions 6, 7 produce rotation of the disc 4 in the reverse direction to that of the roller and change the speed ratio so that the disc 4 re-

volves less than one turn for that number of revolutions of the platen roller 2 corresponding to the upward movement to be performed by the longest paper sheet on which the typing is to be done, besides leaving the required foot margin on the sheet.

In order to set the maximum possible rotation angle of the disc 4 and, consequently to determine the number of turns of the cylinder 2, it is necessary only to introduce the stop 13 into the proper slot 11, the passage from one slot to the next being obtained easily due to the fact that the disc 5 can separate axially from the disc 4 by compressing the spring 14. The operator working on the machine can observe the movement of the stop 13 approaching nearer and nearer to the stop 15 and, when the pitch of the slots corresponds to a single interline space, it will be easy to judge the space still available; the disc 4 is also provided with graduations, not represented, showing the number of lines which are still to be typed and which depends on the angular distance remaining between the two stops.

In the embodiment shown in Figs. 5 to 14 the stop device includes a sleeve 17 and set screws 18, whereby the device may be fixed on the shaft of the platen roller of the machine; interchangeable sleeves such as 19, correspond to different diameters of the axles such as 20.

30 The device includes a disc 21 with openings 22 therein (Figs. 7, 8). A stop-pin 23 with a neck 23a with parallel flats therein can be fixed in any one of these openings, and traverses an opening 24 in a cup-shaped disc 25 which is provided with a pin 26 penetrating into one of a series of holes 27 in the disc 21. Thus one determines and sets, when assembling the device, the relative positions of the cup-shaped disc 25 and of the disc 21, which latter bears graduations and fastenable to the carriage of the machine by a lug plate 28 provided with a sleeve 29 in which the stop 23 penetrates, this plate 28 being then traversed at 30, 31 by fixing screws threaded into the usual carriage. 32 is a movable guiding index in order to allow a quick setting of a part 33a of a movable stop 33 in front of that one of a series of slots 34 which corresponds to the starting position for a determined paper sheet size. Grooves 35, 36, 37 are provided cooperating with a ball 38 pressed by a spring 39, to retain a disc 40 bearing the movable stop 33, in the following positions: (a) Position shown on the drawing wherein the slots 34 and index 32 are released with regard to an elastic stop 41. (b) Release with regard to the stop 41 and the slots 34, but in such a way that a thrust

is developed against the index 32. (c) Position of engagement in the slots 34 and thrust against stop 41. This provision avoids the difficulty which might arise in reading the graduations which are at the back of the machine. The groove 35 is of less depth than the two others in order that, when passing from 35 to 36, the necessary strain should be very small and also to overcome the risk of overrunning the groove 36.

The index 32 is easily adjustable by hand by operating on the part 32^a located above a slide. It can not be displaced by the movable stop 33 which operates only on the extremity of said index, this latter then having a tendency to tilt within the slide. Figs. 13 and 14 clearly show the arrangement of this index 32 with insertion of compressible packing 32^b.

On the sleeve 17 is keyed a pinion 42 meshing with a pinion 43 meshing in turn with a pinion 44 in mesh with the toothed crown 45, the arrangement being such that the rotation of said crown is in the same direction as that of the platen roller of the machine.

The stop 41 is mounted on a lever 46 with opposing spring 47 and oscillates about an axle 48 fastened to the disc 21, the oscillating movement being limited by a slot 49 in the disc 21. This lever 46 drives an elastic arm 50 of a hammer 51 the striking of which against the cup shaped disc 25 produces a signal-sound; Fig. 12 shows that the arm 50 in its resting position is located within a groove of a piece 52 so that a convenient release can take place for the striking of the hammer. In an electrically driven typewriter the movement of the lever 46 can actuate a switch to cut off the electric current and stop the machine.

The graduation can be marked on a removable strip in order to change the graduation corresponding to different platen roller diameters, and multiple graduations can be marked for different line spacings. Two graduations can be provided reading in opposite directions whereby the device may be placed either at the right hand or at the left hand of the machine.

The slots are chamfered at one side of their edges as shown in Fig. 5 when the device is to be placed at the right hand of the machine, and they are chamfered on the opposite side when the device is to be placed at the left hand side. In this case it is sufficient to change the disc provided with these grooves. The chamfering on only one side is for the purpose of avoiding the clamping of part 33^a between the index 32 and the wall of the slot.

The fixation of the disc 21 can be obtained by simply inserting the stop 23 within an opening made in the carriage; however the use of the plate 28, in most of the cases, avoids a manufacturing operation, since the holes 30 and 31 correspond to tapped holes already existing in the usual carriages to receive screws for securing components of the machine; the plate 28 is then inserted between the heads of these screws and the carriage.

In the embodiment shown in Figs. 15 and 16 instead of concentric toothed wheels, bevel gears are used. A plate 53 is fastened to the carriage, a second plate 54 bearing a toothed wheel revolves concentrically with respect to the first one, and is driven by a bevel gear 55 fast on the axle of the machine. The planes of these plates are parallel to this axle, the movable stop 56 is introduced into one of the grooves 57 of the plate 54, the fixed stop being located in 58. This

embodiment is provided with only two grooves 59, 60 instead of the three grooves 35, 36, 37, due to the fact that the need to facilitate the setting at the starting position is not necessary, because the graduation is quite visible.

What I claim as my invention and desire to secure by Letters Patent of the United States is:

1. A platen roller feed regulating device for typewriters comprising an internally toothed crown coaxial with the platen roller, said crown having a series of notches around its periphery, an intermediary pinion in constant engagement with the teeth of said crown, said pinion being rotatable by said platen roller to turn said crown at slow speed relatively to said roller, a stop member rotating with said crown, said stop member being settable coaxially with said crown to engage any of the notches therein, and a fixed stop in the path of said rotating stop member and arranged to block further movement thereof and of the platen roller when said platen roller has turned through a predetermined angle of paper feed.

2. A platen roller feed regulating device for typewriters comprising, a toothed crown disposed with its axis transverse to the axis of the platen roller and having a series of notches concentric with the crown teeth, a bevel pinion in permanent gear with said crown teeth, said pinion being rotatable by said platen roller to turn said crown at slow speed relatively to said roller, a stop member rotating with said crown, said stop member being settable coaxially with said crown to engage any of the notches therein, and a fixed stop in the path of said rotating stop member and arranged to block further movement thereof and of the platen roller when said platen roller has turned through a predetermined angle of paper feed.

3. A platen roller feed regulating device for typewriters comprising an internally toothed crown coaxial with the platen roller, said crown having a series of notches chamfered on one edge around its periphery, an intermediary pinion in constant engagement with the teeth of said crown, said pinion being rotatable by said platen roller to turn said crown at slow speed relatively to said roller, a stop member rotating with said crown, said stop member being settable coaxially with said crown to engage any of the notches therein, and a fixed stop in the path of said rotating stop member and arranged to block further movement thereof and of the platen roller when said platen roller has turned through a predetermined angle of paper feed.

4. A device according to claim 1 wherein the platen roller has a shaft to which the toothed crown is concentric and is permanently in mesh with said intermediary pinion which is itself constantly in mesh with another pinion fast on said shaft.

5. A device according to claim 1 wherein the platen roller has a shaft to which the toothed crown is concentric and is permanently in mesh with said intermediary pinion which is itself constantly in mesh with another pinion fast on said shaft, said device also comprising three discs loose on said roller shaft, the first of these discs being fixed to the typewriter and carrying said intermediary pinion, said second disc carrying the internally toothed crown with said series of notches provided externally thereon, and said third disc carrying said settable stop member.

6. A device according to claim 1 wherein said fixed stop comprises a spring permitting slight

oscillation, and comprising a sound-signal lever actuated by said oscillation when said fixed stop is encountered by the settable stop member.

7. A device according to claim 1, comprising an index of the writing line position, a support for the settable stop, and spring and ball retaining means for holding said support in three positions, the first one in which said settable stop is re-

leased with regard to the fixed stop, the notches and said index, the second in which said settable stop is released with regard to the fixed stop and the notches but exerts thrust on said index, and the third position in which said settable stop is engaged in the notches and follows a path wherein it will encounter said fixed stop.
